UNITED STATES PATENT OFFICE.

HARVEY M. WESCOTT, OF BROOKLYN, NEW YORK.

MECHANIC'S LEVEL.

Application filed April 11, 1927. Serial No. 182,798.

This invention relates to an improved level which is especially, but not necessarily, adapted for use by mechanics in construction work of all kinds.

5 Briefly, the improvement is directed to a means which is associated with a spiritlevel to permit measurements of inclined surfaces.

Broadly, the improved structure embodies a base, a level hingedly connected thereto, 10 means for adjusting the level toward and from the base, and a measuring tape connected to and operated by the base and level respectively.

The specific details, as well as their particular association and arrangement will become more readily apparent from the following description and drawings.

In the accompanying drawings forming a part of this application and in which like 20 numerals are employed to designate like parts throughout the same:—

Figure 1 is a perspective view of a device constructed in accordance with the present invention showing the parts or sections 25 closed.

Fig. 2 is also a perspective view showing the parts open.

Fig. 3 is a view in section and elevation, observing the sides of the device, and showing one method of using the same.

Fig. 4 is an end view showing the sections separated.

Fig. 5 is a section taken approximately upon the plane of the line 5—5 of Fig. 1.

35 Referring to the drawings in detail, it will be seen that the reference character 1 designates what may be broadly referred to as a base or lower section. Specifically, this comprises a hollow box of elongated rectangular configuration forming a flat bottom and being open at its top. A cover plate 2 is fastened to the open top and is provided with an elongated slot terminating at one end in a cross-head opening 4.

40 The box is notched at one end, as indicated at 5. Swivelly mounted as at 6 in the last-named end of the box is a rotary screw shaft 7, which extends through the front end of the box, and is provided with a turning knob 8. Located in the interior is a retaining collar 9. Attached to one side wall and at the forward end of the box is a circular casting 10 containing a spring wound drum (not shown), on which a measuring tape is wound.

55 This measuring tape extends upwardly through a small slot in the top plate as shown.

At its upper end, it is fastened to the forward end of a level 12. The level comprises an elongated wooden slot provided with a set of three spirit levels 13 of conventional construction. Two of the levels are arranged on top and one on the side, so that the device may be used for either horizontal or vertical surfaces in the customary manner.

At the opposite end of this level section 12 is a depending ear 14 located in the aforesaid notch 5 and hingedly connected to the base section 1. A nut 15 is mounted on the shaft 7, a link 16 is connected thereto, and is also connected with a bracket 17 fastened to the under side of the hingedly mounted level section 12. Obviously, by rotating the knob 8, the shaft 7 will be turned to feed the nut 15 back and forth on the screw threads of the shaft.

This section will raise and lower the level section 12 upon its hinge connection. In so doing, it will actuate the measuring tape 11 in an apparent manner. The tape is of course provided with graduations of a suitable character, so that the space between the two sections of the device may be accurately ascertained.

From the foregoing description and drawings it will be plain that I have evolved and produced a simple and inexpensive device which may be employed in construction work for the approximate degree of inclination of any surface with respect to a horizontal line. To persons skilled in the art, it is evident that the shaft 7 must be operated to raise or move the level to a substantially horizontal position, which position is indicated by the spirit levels carried thereon. Obviously when this part 12 is in a horizontal position, and the flat bottom of the base section is placed against the inclined surface, the graduations on the measuring tape will enable the operator to determine the degree of inclination of the surface with respect to a horizontal measuring line.

The construction, as well as the method and use of the invention will be clear, it is believed, when the description is considered carefully in connection with the drawings. Therefore, a more lengthy description is thought unnecessary.

While the preferred embodiment of the invention has been specifically shown and described, it is to be understood that minor changes coming within the field of invention claimed, may be resorted to if desired.

Having thus described my invention, what I claim as new is:—

In a level of the class described, a box-like base section, a longitudinally disposed screw threaded shaft mounted for rotation in said base section, a relatively movable cover section cooperable with the base section, spirit levels on said cover section, a hinge connection between one end of the movable cover section and said base section, a casing located in and carried by said base section, a drum in said casing, a measuring tape wound upon

said drum, the free end of said tape being connected with the swingable end of said movable section, a nut movable along the 15 screw threads on said shaft, a bracket carried by the movable section, and an operating link pivotally connected to said nut and to said bracket, whereby when said shaft is rotated, said movable cover section will be moved toward and from the base section in order to actuate the measuring tape.

In testimony whereof I affix my signature.
HARVEY M. WESCOTT.
